UNITED STATES PATENT OFFICE

2,079,128

FACIAL APPLIANCE

Jane McKinlay, Los Angeles, Calif.

Application March 23, 1936, Serial No. 70,356

4 Claims. (Cl. 128—76)

This invention relates to facial appliances.

The general object of the invention is to provide an improved facial apparatus which produces a face lift as soon as applied.

A more specific object of the invention is to provide a facial apparatus including novel members adhesively connected to the face of the wearer and connected together so that there will be a lifting of the flesh.

Another object of the invention is to provide a facial apparatus including connected tabs which are adapted to engage the wearer in front of and behind the ear.

Other objects and the advantages of the invention will be apparent from the following description taken in connection with the accompanying drawing, wherein:

Fig. 1 is a view showing a head with one of my improved facial appliances thereon and with the hair drawn back to expose the tab;

Fig. 2 is a perspective view of the facial appliance;

Fig. 3 is a side elevation of my appliance with a portion thereof removed;

Fig. 4 is an enlarged section in detail taken on line 4—4 of Fig. 2;

Fig. 5 is a perspective view showing the manner in which the tunnels are made;

Fig. 6 is a face view of a modified form of tab;

Fig. 7 is a section taken on line 7—7 of Fig. 6;

Fig. 8 is a view similar to Fig. 6, showing a further modification; and

Fig. 9 is a section taken on line 9—9 of Fig. 7.

Referring to the drawing by reference characters I have shown my appliance as embodied in a device which is indicated generally at 10. As shown this device comprises a pair of tab members 11 which are connected by a ribbon 12 which may be made of silk and which includes an adjusting buckle 13.

The tabs are similar except that they are rights and lefts and a description of one will suffice for both.

As shown each tab comprises a layer of flexible material such as cloth 14 the faces 15 and 16 of which are each covered with an adhesive. The adhesive on the face 15 is of such a material that it will not dry out and will not injure the skin of the wearer. On this face 15 I arrange a removable sheet 16' of transparent regenerated cellulose such as cellophane.

Each tab comprises a body 17 which is adapted to be disposed just in front of the ear of the wearer and an extension 18 which is elongated

and curved and which is adapted to fit behind the ear of the wearer. The parts 17 and 18 have a plurality of apertures 19 at their juncture by means of which the parts may be torn apart or cut apart in case the part 18 is not to be used, which frequently occurs, depending on the facial contours to be produced.

The regenerated cellulose covering 16' extends over the extension 18 as well as the tab 17. On the face 16 of the tab portion 17 I arrange, during the process of manufacture, a plurality of wires 20 which have paper strips 20' wrapped thereabout as shown in Fig. 5. These wires with the paper strips form tunnels 21 which are laid upon the tab in the desired relation, here shown as parallel, and then a fabric cover 22 is placed over the fabric layer 14. This cover 20 extends onto the extension 18 as well as the tab 17 and the adhesive on the face 16 unites the layers 14 and 22 and also holds the paper wrapped wires 20 in place. As soon as the parts are made the wires 20 are withdrawn leaving the paper in place to provide the tunnels 21.

Between the layers 14 and 22 I secure the end 23 of a ribbon 24. This ribbon has a loop 25 which is inserted in one slot of the buckle 26, while the ribbon 12 is inserted in the other slot of the buckle 26. I preferably provide adhesive at 27 on the inner ribbon end 23 to hold this end in position.

In use the regenerated cellulose coverings 16' are removed and the tabs 17 with the extensions 18 are adjusted in front of and behind each ear of the wearer. The tabs extend down to approximately the middle portion of the ear in front, and rearwardly the extensions extend to the bottom of the ear. The buckle 13 is then adjusted and the ribbon 12 run through the hair across the top of the head, the tension in the ribbon causing an upward urging or lifting of the tabs so that the flesh to which the tabs is attached is also urged upwardly or lifted.

With some persons the extensions 18 may be omitted and in this case the tabs are separated along the perforations 19 by tearing or cutting. It will be understood, of course, that the tabs may be initially made without the extensions 18.

After the tabs have been placed and the buckle adjusted the hair is arranged over the tabs and hairpins 28 are inserted through the tunnels 23 so that the tabs will be entirely hidden from an observer. It will be understood that the interior diameter of the tunnels 23 is approximately the same as that from which the hairpins are made.

so that the hairpins will be firmly held in place in the tunnels.

In Figs. 6 and 7 I have shown a modification of my invention wherein the tab 30 comprises a plurality of layers 31 and 32 and wherein the edges are provided with stitches 33 to hold the parts assembled. A transparent layer of material 34 is disposed over the adhesive material on the outer surface of the layer 31 and a ribbon 35 10 is secured by the stitches 33. The ribbon 35 may be attached to a loop as previously described. Tunnels 35' similar to the tunnels 21 are shown as disposed between the layers 31 and 32.

In Figs. 8 and 9 I have shown a modification 15 of my invention wherein layers 36 and 37 are connected by adhesive 38 and wherein adhesive 39 holds a removable, transparent layer 40 in place. Between the layers 36 and 37 I arrange a wire 41 which includes an end 42, a loop 43, 20 and an intermediate portion 44 which passes diagonally across a corner of the tab and projects therefrom as at 45, whence the extreme end 46 is bent to position upon the outer face of the tab so that the end 46 may be engaged by a hairpin. In addition to the wire 41 I may employ tunnels 47 similar to the tunnels 21 which are shown between the layers 36 and 37. These tunnels extend only part way across the tab.

It will be understood that the manner of using 30 the device shown in Figs. 6 to 9, inclusive, is the same as that set forth in the preceding description.

From the foregoing description it will be apparent that I have provided a novel facial appliance which can be economically manufactured and readily applied and which does not interfere with the comfort of the wearer, although it does greatly improve the appearance of the wearer.

40 Having thus described my invention I claim:
1. In a facial apparatus, a plurality of tabs;

flexible means connecting said tabs, each of said tabs comprising a layer of fabric having an adhesive on one face thereof, each of said tabs including a body portion, a plurality of hollow open ended rolls arranged on the other face of said tab, and a covering on said other face of the tab and engaging the tab and the rolls.

2. In a facial apparatus, a plurality of tabs, flexible means connecting said tabs, each of said tabs comprising a central layer of fabric having an adhesive on one face thereof, each of said tabs including a body portion having an elongated extension thereon, a plurality of hollow paper rolls arranged on the other face of said tab, a covering on said other face of the tab and 10 engaging the tab and the rolls.

3. In a facial apparatus, a plurality of tabs, flexible means connecting said tabs, each of said tabs comprising a central layer of fabric having an adhesive on each face thereof, each of said tabs including a body portion having an elongated, curved extension thereon, there being a plurality of perforations at the juncture of said tab and its extension, a plurality of hollow paper rolls arranged on one face of said tab, a covering on said one face of the tab and engaging the tab and the rolls, and a removable transparent covering on the other face of the tab.

4. In a facial apparatus, a pair of tabs, each of said tabs comprising two layers of cloth, means 30 connecting said tabs, said tabs having tunnels extending therethrough from one edge to the other and adapted to receive a hairpin, said tabs including a curved portion extending below the lower end of the tab, said tab having adhesive 35 coating thereon, said tab being adapted to be disposed in front of the ear of the wearer and said extension being adapted to be disposed in the rear of the ear of the wearer.
